(57) **CLAIM**

The ornamental design for a tongue scraper, as shown and described.

DESCRIPTION

FIG. 1 is a perspective view of a tongue scraper showing my new design;

FIG. 2 is a front plan view thereof;

FIG. 3 is a back plan view thereof;

FIG. 4 is a left plan view thereof;

FIG. 5 is a right plan view thereof;

FIG. 6 is a top plan view thereof;

FIG. 7 is a bottom plan view thereof;

FIG. 8 is another perspective view thereof; and,

FIG. 9 is a section view thereof taken along cutting plane 9 shown in FIG. 3.

The broken lines shown in the drawings illustrate portions of the tongue scraper that form no part of the claimed design.

1 Claim, 6 Drawing Sheets
